ATTORNEYS

UNITED STATES PATENT OFFICE.

FRED GRUNDY, OF CONIMICUT, AND WINFIELD E. GRAY, OF PAWTUCKET, RHODE ISLAND.

POURING-SPOUT CAN ATTACHMENT.

Application filed February 13, 1924. Serial No. 692,477.

To all whom it may concern:

Be it known that we, FRED GRUNDY and WINFIELD E. GRAY, citizens of the United States, residing at Conimicut and Pawtucket, respectively, in the counties of Kent and Providence, respectively, and State of Rhode Island, have invented certain new and useful Improvements in Pouring-Spout Can Attachments, of which the following is

10 a specification.

This invention relates to a pouring spout attachment for cans, other receptacles and the like.

It is aimed to provide a novel and generally improved attachment which may be readily applied to and detached from the can or the like and one which particularly may have its outlet normally closed so as to keep the same sanitary and afford compliance with the laws of many States in that regard.

Additional and servient objects and advantages will become apparent from a consideration of the description following taken in connection with the accompanying drawings illustrating an operative embodiment.

In said drawings:—

Figure 1 is a plan view of the attachment;

Figure 2 is a longitudinal vertical substantially central sectional view thereof;

Figure 3 is an end elevation; and

Figure 4 is a sectional view taken on the line 4—4 of Figure 1.

Like reference characters designate like or corresponding parts in the different views.

In carrying out the invention, a bell-shaped body 10 is provided whose side wall 11 adjacent the distal edge is grooved at 12 so that a rubber gasket 13 will clasp therein removably and project below said edge to engage a can or the like when the device is used.

A can-puncturing and securing blade 14 is disposed centrally of the body 10 and has a shank 15 reduced and formed into a square stud 16 removably fitting a square opening 17 in the closed upper wall 18 of the body 10. A set screw 19 is threaded into the shank so as to secure the shank 15 in place and a closure plate 20 in place, contacting the wall 18, since the screw

passes through the latter and its head 21 overlaps the same.

Plate 20, as suggested by dotted lines in Figure 1 and full lines in Figure 2, normally closes the outlet ends of the tubes 22 which may be soldered or otherwise fastened to the side wall 11 of body 10 at diametrically opposite points and relatively close to the distal edge. Said tubes extend angularly outward and upward and their free ends terminate in the same plane as the upper surface of wall 18. Plate 20 is pivoted on the screw 19 and frictionally engages wall 18 so that it may be moved from the dotted line position of Figure 1 to the full line or open position of the same figure and of itself remain in either position, and diagonally opposite corners may be cut away or notched at 23 so that the tubes may be uncovered by slight movement of the plate 20 and also to enable said plate to be better gripped or engaged by the fingers to move it.

Blade 14 is substantially shaped similar to an arrow head as it has a penetrating point 24, side edges 25 at intersecting angles and sharpened to a feather each from a different side of the blade and has upper surfaces 26 inclined along intersecting angles a short distance below the distal edge of the body. An opening 27 is provided through the blade 14.

In use, blade 14 with point 24 foremost may be thrust into a tin can or the like containing for instance, evaporated milk or other material adapted to be dispensed periodically. This punctures the can and provides a substantially rectangular opening after which the body is turned about ninety degrees to the position of insertion to the end that the gasket 13 will be drawn tight against the upper surface of the can under the cam action of inclined edges 26 as cams. Sufficient pressure is thus provided to maintain the attachment in this position against accidental detachment. When thus turned, only shank 15 is disposed in the puncture and hence when the can is inverted or tilted, the contents is free to escape from the unclosed portions of the puncture into the body 10 and from the same through tubes 22, which are uncovered at the proper time by swinging the closure plate 20 from the dotted line position of

Figure 1 to the full line position thereof. When the device remains on the can between the periods of dispensing, the closure plate covers the tubes 22 so that the same may be kept sanitary and will comply with health regulations. The device after use on one can may be readily removed, attached to and used on other cans. Also when the material is escaping from one tube, the device is usually held at such an angle that air enters the can through the other tube. Opening 27 prevents undue obstruction to the flow of the material from the can since the latter may pass through blade 14.

We claim as our invention:

A pouring attachment having a bell-

shaped body, tubes extending outward and upward from its side wall and terminating in substantially the same plane as the top 20 of the body, said top having a square opening therethrough, a shank having a square portion fitting said opening, a closure for said tubes frictionally engaging said top, a fastening having a head overlapping the 25 closure, said fastening passing through and pivotally mounting the closure and extending removably into the square portion, and a puncturing and securing blade on the shank below the body. 30

In testimony whereof we affix our signatures.

FRED GRUNDY.

WINFIELD E. GRAY.
